PROCESS FOR PRODUCTION OF HIGH
QUALITY PETROLEUM PRODUCTSErving Arundale and Louis A. Mikeska, Westfield,
N. J., assignors to Standard Oil Development
Company, a corporation of Delaware

Application January 12, 1949, Serial No. 70,424

10 Claims. (Cl. 196—40)

1

The present invention is concerned with an improved process for the production of high quality petroleum products, especially petroleum products boiling in the motor fuel boiling range. The invention is more particularly concerned with the treatment of cracked petroleum hydrocarbons boiling in the motor fuel boiling range for the production of gasolines which are substantially completely free of undesirable constituents which cause corrosion, varnish and valve deposits in an internal combustion engine. In accordance with the present invention, petroleum hydrocarbons, particularly cracked petroleum hydrocarbons are contacted under controlled conditions with relatively dilute acids containing critical amounts of an aldehyde, particularly formaldehyde.

In the production of high quality petroleum products as for example in the production of petroleum products boiling in the motor fuel boiling range it is known to use various procedures. These procedures in general are directed toward removing constituents from the motor fuels which cause harmful results to the engine when consumed. The procedures also are directed toward retaining in the gasolines the desirable constituents and also directed toward securing maximum yields of the desired products. In the chemical treatment of petroleum fractions boiling in the motor fuel boiling range, the use of concentrated sulfuric acid is well known. This acid removes sulfur compounds as well as various unsaturated diolefins and related compounds which cause deleterious results in the engine when the fuel is burned. While the use of sulfuric acid produces a satisfactory product certain problems exist with respect to its use. When a cracked stock is treated with sulfuric acid for the removal of mercaptans and other sulfur compounds as well as olefinic constituents, excessive polymerization of both the desirable and undesirable hydrocarbon constituents occurs, resulting in an increase in the loss of gasoline to higher boiling polymers. Furthermore, when a relatively large quantity of sulfuric acid is used which is necessary under cer-

2

tain conditions, in order to satisfactorily free the hydrocarbon fraction of undesirable constituents it is necessary to subsequently sweeten the gasoline, usually by means of the so-called "doctor treat."

A new process has now been discovered for the production of high quality petroleum products, particularly gasolines. In accordance with the present invention petroleum fractions particularly cracked petroleum fractions are treated with dilute acids in the presence of a controlled amount of an aldehyde as for example formaldehyde. The invention is especially concerned with the use of sulfuric acid having a concentration not in excess of about 90% and preferably having a concentration in the range from about 30-80%. A particular desired acid concentration for use in accordance with the process of the present invention is a sulfuric acid having a concentration in the range from about 55-65%. The amount of aldehyde employed is in the range of about .5 to 5% and is preferably in the range from about 1.5 to 3.0%. The preferred aldehyde comprises formaldehyde.

25 The process of the present invention may be more readily understood by the drawing illustrating embodiments of the same. Referring to the drawing, a feed oil, which for the purpose of illustration is assumed to be a gas oil boiling in the range from about 400° F. to 700° F., is introduced into cracking zone 10 by means of feed line 1. It is to be understood that the feed oil may comprise a reduced crude or similar cracking feed stock. Cracking zone 10 may comprise either a catalytic or thermal cracking zone. Temperature and pressure conditions, as well as, feed rates in zone 10 are adapted to secure the desired cracking of the feed stock.

30 40 The cracked products are withdrawn from zone 10 by means of line 2 and introduced into distillation zone 20 which may comprise any desirable number of stages. Hydrocarbon products boiling below the gasoline boiling range are withdrawn from zone 20 by means of line 3, while a hydrocarbon fraction boiling in the

motor fuel boiling range is withdrawn from zone 20 by means of line 4 and introduced into storage zone 5. Also, for the purpose of illustration it is assumed that a hydrocarbon fraction boiling in the kerosene boiling range is removed from zone 20 by means of line 6 and introduced into storage zone 7. Hydrocarbon fractions boiling in the diesel fuel boiling range are removed from zone 20 by means of line 8 and introduced into storage zone 9. Higher boiling hydrocarbons are withdrawn from zone 20 by means of line 11 and further distilled or handled in any manner desired.

In accordance with conventional practice, the respective streams from zones 5, 7 and 9 are individually treated as follows. For purpose of illustration the treatment of the hydrocarbon fraction boiling in the motor fuel boiling range is described.

The hydrocarbon fraction is withdrawn from storage zone 5 by means of line 12 and combined with concentrated sulfuric acid having the concentration in excess of about 95 weight per cent which is introduced into the system by means of line 13. Satisfactory mixing is secured by passing the streams through orifice mixing devices 14 and then introducing the stream into settling zone 30. Acid sludge is withdrawn from zone 30 by means of line 15 while the treated oil is withdrawn by means of line 16. Water is introduced into the system by means of line 17 and the oil and water pass through orifice mixing devices 18. The mixture is introduced into zone 40 and a water layer withdrawn by means of line 19. The oil layers withdrawn by means of line 21 are combined with dilute caustic which is introduced by means of line 22. Mixing is secured by orifice mixing devices or equivalents 23. The stream is introduced into zone 50 from which a spent caustic phase is withdrawn by means of line 24. The oil phase is withdrawn by means of line 25 and introduced into distillation zone 60. Hydrocarbon constituents, as for example polymerized hydrocarbons boiling above the motor fuel boiling range, are withdrawn from zone 60 by means of line 26, while the hydrocarbon fractions boiling in the motor fuel boiling range are withdrawn from zone 60 by means of line 27. This stream is then passed into treating zone 70 wherein the same is treated with a doctor solution in order to convert objectionable sulfur compounds into relatively harmless disulphides. The final product is withdrawn from zone 70 by means of line 28.

In accordance with the present invention the cracked product is treated with a dilute acid, preferably a dilute sulfuric acid containing a critical amount of an aldehyde, preferably a formaldehyde. In accordance with a preferred adaptation of the invention, the formaldehyde is introduced into the oil stream by means of line 29 and the oil and formaldehyde mixed in orifice mixer or equivalent 80. The acid is then added as described by means of line 13. It is, however, to be understood that the formaldehyde may be added to the acid and the dilute acid containing the formaldehyde then contacted with the oil. When operating in accordance with the present invention the overhead stream removed from zone 60 by means of line 27 comprises a finished product and it is thus possible to by-pass doctor treating zone 70. The finished product is removed from the system by means of line 31.

The present invention may be more fully understood from the following examples illustrating various embodiments of the same.

EXAMPLE 1

A thermally cracked hydrocarbon fraction boiling in the gasoline boiling range (60° F. to about 400° F.) was treated at 70° F. with 60% sulfuric acid containing 5% by weight of formaldehyde based on gasoline fed. The volume of acid used per volume of oil was 20%. The acid layer was separated from the oil layer. The oil layer was water washed, caustic washed and then steam distilled. The results of this treatment are as follows:

TABLE I

	Diolefin Content	Copper Dish Gum, Mg./100 cc.	ASTM ¹ Break-down	Peroxide No. ²	Total Sulfur
Untreated Fraction	Per cent 2.95	196	185	1.1	Percent 0.137
Treated Fraction	1.46	5	1,440+	0.2	0.046

¹ ASTM designation D 525-46.

² Milliequivalents of peroxide O₂ per liter.

It is readily apparent that the quality of the treated cracked stock is very much improved.

EXAMPLE 2

A steam cracked hydrocarbon fraction boiling in the range from about 185-400° F. was treated similarly as described in Example 1. The results of these tests are as follows:

TABLE II

	Diolefin Content	Copper Dish Gum	ASTM Break-down	Peroxide No.
Untreated	17.5	2	230	0.2
Treated	3.3	2	1,340	0.2

It is evident from Examples 1 and 2 that the treatment of the cracked distillates produced a reduction of diolefin concentration, sulfur, copper dish gum and an improvement in oxidation stability, and thus improved their quality.

EXAMPLE 3

A gasoline feed stock was prepared by blending the following two gasolines in equal proportions. One was a gasoline distillate from reduced crude and whole crude cracking which was very sour and relatively stable. The second was a gasoline distillate from naphtha reforming which was quite unstable but substantially sweet. The resulting blend was therefore both sour and unstable. It contained 0.26% sulfur, 2.75% diolefins, and boiled between 150° F. and 430° F. In operations G to K the concentration of the sulfuric acid strength was varied while in operations A to F the concentration of the acid strength was also varied in the presence of 5% formaldehyde based on the weight of the hydrocarbon fraction. In all cases 20% of the acid solution was employed based upon the volume of the oil being treated. The treated fractions were finished in a manner similar to that described in Examples 1 and 2. The results of these operations are listed in the following Tables III and IV.

J	30	60	600	12	—	0.234	44.4	2.45
K	20	85	704	16	0.6	—	46.9	—

¹ General operating conditions utilized: 20 vol. per cent of acid solution on gasoline, 6 hours at 25° C. Steam distillation of treated gasoline.

² M. g. mercaptan sulfur/100 cc.

³ Gram equivalents active oxygen/1000 liters.

⁴ Centigrams of bromine/gram.

⁵ Control-water washed, neutralized with NaOH, and steam redistilled.

From the data presented in Tables III and IV, it is apparent that the stability as measured by the ASTM breakdown test is improved. It is also apparent that the sulfur and gum content are reduced as the catalyst concentration is increased. Furthermore, it is apparent that the gasolines treated with formaldehyde in the presence of dilute sulfuric acid possess superior stabilities, lower sulfur contents, lower gum contents, better peroxide numbers, improved copper numbers and improved diene contents than gasolines treated with dilute acids in the absence

of formaldehyde. A very desirable acid concentration is about 50-60%.

EXAMPLE 4

Additional operations were conducted varying the amount of 60% H_2SO_4 employed, the formaldehyde concentration and the time of contact employing 60% sulfuric acid concentration. The results of these operations are presented in Tables V, VI, VII. The treated products were finished as described in Examples 1, 2, and 3.

TABLE V
Effect of Catalyst Solution Volume

[General operating conditions: 60% H_2SO_4 catalyst, 5 wt. per cent CH_2O on gasoline, 6 hour contact at 25° C.]

Run	Vol. Per Cent H_2SO_4 Sol.	ASTM Break- down	Cu Dish Gum	Copper No.	Peroxide No.	Total Sulfur	Br. No.
A	20	810	32	≤1	0.2	0.078	31.8
B	10	755	34	≤1	0.2	0.112	34.1
C	5	755	95	≤1	0.2	0.161	36.2

TABLE VI

Effect of Formaldehyde Concentration[General operating conditions: 20 vol. per cent 60% H_2SO_4 catalyst. 6 hour contact time at 25° C.]

Run	Per cent CH_2O by Wt. on Gasoline	ASTM Break-down	Cu Dish Gum	Copper No.	Peroxide No.	Total Sulfur	Br. No.
A	5	810	32	<1	0.2	0.078	31.8
B	2.5	580	-----	<1	0.1	0.144	36.4

D	0.65	540	20	4	0.2	0.147	43.4
E	0	275	61	5	0.4	0.188	41.5

TABLE VII

Effect of Contact Time at 25° C.[General conditions: 20 vol. per cent 60% H_2SO_4 catalyst. 2.5 wt. per cent CH_2O on gasoline.]

Run	Contact Time	ASTM Break-down	Cu Dish Gum	Copper No.	Peroxide No.	Total Sulfur	Br. No.
	Hours						
A	6	580	287	<1	0.1	0.144	36.4
B	3	680	15	<1	0.1	0.119	38.0
C	1	550	4	<1	0.2	0.122	35.9

From Table V it is apparent that an increase in the volume of acid catalyst solution produces a reduction in the sulfur content with very little effect on the breakdown, the gum, the copper number and the peroxide number. A preferred treat of 60% concentrated acid (H_2SO_4), is about 10 to 20% by volume of acid per volume of oil.

It is also apparent that an increase in the formaldehyde concentration produces an improvement in the breakdown characteristic, a reduction in the copper number, a reduction in the sulfur content without appreciably effecting the peroxide number or gum content.

Also when the contact time is increased, the gum and sulfur contents are increased without changing the stability, copper number or peroxide number. It is therefore apparent that short contact times are desirable.

It is to be noted that the copper dish gum values as shown in Examples 3 and 4 are relatively

tively high due probably to the fact that the condensation products of formaldehyde with the undesirable gasoline constituents distill overhead with steam but do not evaporate in the copper dish gum determination. Superior results can be obtained particularly as regards gum content of the finished gasoline by distilling the treated product dry instead of in the presence of steam as is shown by the examples.

EXAMPLE 5

Additional operations were conducted wherein the treated cracked gasolines were removed from the acid layer, neutralized with caustic soda, water washed and rerun in the absence of steam to an end point of 400° F. The effects of varying; formaldehyde concentration, acid solution volume and temperature were also determined. The results are listed in Tables VIII, IX, X, and XI.

¹ Material boiling above 400° F. expressed as per cent of volume of original feed.

From Table VIII it is apparent that strong concentrated sulfuric acid per se is not particularly desirable in that the extent of polymer formation is relatively high. Table IX indicates that a preferred concentration of formaldehyde is in the range from about 1½ to 3%.

The data also show in Table X that by increasing the acid solution volume a reduction in gum content, a reduction in peroxide number and a reduction in sulfur with no appreciable effect on breakdown or copper number is secured. In a continuous process the use of 5 volume % by acid is adequate. It is apparent (Table XI) that by

products may be somewhat greater. Formalin (37% formaldehyde solution in water) can be used in place of paraformaldehyde by adding concentrated sulfuric acid thereto and adjusting the acid solution concentration to the desired level with water.

40

EXAMPLE 6

Additional operations were conducted wherein the time of contacting was varied and the product redistilled. The results of these operations are given in Table XII.

increasing the treating temperature, the sulfur content is slightly reduced as well as the gum content. However, the stability, the copper number and the peroxide number are not substantially changed. It is also apparent that as the contact time is reduced, the sulfur and peroxide contents increase.

Gasolines treated with acetaldehyde (in molar equivalent quantities) possess properties substantially equal to those treated with formaldehyde although the loss of gasoline to higher boiling

65 Although rerunning is necessary to reduce the sulfur, the gum and the peroxide contents and to improve the stability, the mercaptan content can be greatly reduced even without rerunning. Furthermore, the acid layer can be recycled, but its acid concentration should be held constant in order to secure uniform removal of the sulfur.

EXAMPLE 7

75 The value of a formaldehyde dilute acid treat over a conventional concentrated acid treat is

further illustrated by the following operational data: (Table XIII).

At the end of 40 hours operation, the engine was dismantled and inspected. The deposits on

TABLE XIII
Comparison of formaldehyde and acid treating

Run	Treat	ASTM Break-down	Cu Dish Gum	Diolefine Content	Total Sulfur	Br. No.	Peroxide No.	Motor O. N. Δ +2 cc.		
								Clear	Pb	O. N.
A	(10% vol. per cent 60% H_2SO_4 sol. 2% CH_2O on gasoline 1 hour at 25° C.)	500	18.0	Per cent 1.55	Per cent 0.127	40	0.4	69.6	77.5	7.9
B	5% $bb.$ conc. H_2SO_4 treat. 1 hour at 25° C.	205	7.2	0.37	0.100	40.5	0.0	69.5	77.4	7.9
C	10 vol. per cent water control (1 hour at 25° C.)	125	303	2.25	0.230	51.7	2.2	70.8	76.3	5.5

From the above it is apparent that although the diene content is somewhat higher, the formaldehyde treated distillate possesses somewhat better stability (as measured by ASTM breakdown test) than the concentrated acid treat. This would indicate that the formaldehyde-dilute acid process is more selective. In addition, the same gasoline lead susceptibility is obtained as can be obtained with the strong sulfuric acid process, but the sulfur content of the formaldehyde treated distillate is not as low as that of the acid treated distillate.

EXAMPLE 8

Engine test data have indicated that the thermal and catalytic naphtha fractions of the finished gasoline apparently contain the major varnish and sludge forming and stability reducing constituents. In order to demonstrate the superiority of the formaldehyde dilute acid treatment over the concentrated sulfuric acid treatment as a means of improving the engine cleanliness characteristics of gasolines, further operations were conducted on a blend containing 90% untreated thermal naphtha and 10% heavy catalytic naphtha. The treating results obtained on this blend are listed in Table XIV.

TABLE XIV

Run	Treat	Treating Losses ¹		Total	Motor Octane No.	Engine Test, per cent of reference
		Sludge	Polymer			
1	Blend rerun to 400° F. vapor temperature					
2	Blend treated with 66° B6. H_2SO_4 (5 lbs./bbl.), water washed, neutralized and rerun to 400° F.	2.2	3.2	5.4	71.3	144
3	Blend treated with 1.5 wt. per cent formaldehyde in the presence of 10 Vol. per cent, 60% H_2SO_4 , 1/2 hr. contact time finished as in run 2.	3.0	0.4	3.4	71.3	113
4	Same as run 3 but employing 3 wt. per cent formaldehyde	2.6	2.2	4.8	70.3	100

¹ As per cent by volume based on feed.

It will be noted that the loss of gasoline to higher boiling polymer is lower on formaldehyde dilute acid treating than on concentrated sulfuric acid treating in the absence of formaldehyde. Samples of the treated gasolines were then run in a single cylinder Lauson engine operated under the following conditions:

Engine Speed, R. P. M.	1800
Crankcase Temp., °F	145
Jacket Temp., °F	95
Intake Air Temp., °F	120
Oil Charge, Quarts	0.5
Test Duration, Hours	40
Power Output, H. P.	2.2
Crankcase Vent, C. F. H.	0.75

valves, pistons, rings and combustion chamber 20 were noted and the sludge in the lubricating oil measured. All these factors were taken into consideration in evaluating the engine cleanliness characteristics of the gasoline run.

25 The results secured were compared to the results secured when running a high quality and satisfactory gasoline considered as a reference fuel and rated as 100%. From the data it is evident that the use of formaldehyde markedly improves the engine cleanliness characteristics 30 of the motor fuel. It is also evident that the dilute acid treat plus formaldehyde is superior to the concentrated acid treat, as a means of improving the engine cleanliness characteristics of thermally and catalytically cracked fuels.

35 The present invention is concerned with the production of high quality petroleum oil products. The invention is particularly directed to an improved process for improving the engine cleanliness characteristics and oxidation stability 40 of motor fuels especially thermally and catalytically cracked gasolines. The invention is also directed toward the production of gasolines having lower sulfur, gum, diene, and peroxide contents thereof. The process employed broadly

utilized a dilute treating acid, preferably a sulfuric acid having a concentration not in excess of about 80% and preferably having a concentration in the range from about 55% to 65% in conjunction with an aldehyde, preferably formaldehyde.

65 The stock treated may have a boiling range from about 50° F. to 700° F. although it is preferred that the final boiling point be not in excess of 450° F. It is also preferred that the bromine number of the feed be at least 15 C. g. Br./gm. The process can also be applied to the treatment of other hydrocarbon distillates such as heavy naphthas, kerosenes, heating oils, diesel 70 fuels and the like. It is to be understood that

the entire fraction may be treated or that specific boiling range fractions may be segregated and separately treated. Various cycle stocks secured from refining operations can likewise be treated in the manner described.

With respect to the method of treatment, it is preferred that the formaldehyde be added to the oil and mixed therewith followed by the addition of acid. It is, however, to be understood that the formaldehyde can be added to the acid and this mixture used to contact the oil. The acid layer segregated from the oil containing the formaldehyde may be recycled in order to contact fresh untreated oil. If sulfuric acid be used, it is preferred that the concentration be in the range from about 30% to 80%, preferably in the range from 55% to 65%. The amount of acid solution used is preferably from about 0.5 to 10 volume per cent based upon the gasoline. The aldehyde concentration used is in the range from 0.5 to 5% preferably from 1½ to 3% by weight based upon the gasoline. The concentration of the aldehyde employed will to some extent depend upon the unsaturation of the stock being treated. The time of contact may be as high as 60 minutes, although it is preferred that it not exceed 15 to 30 minutes. The temperature of contacting also is preferably in the range from about 20 to 60° C. Other acids of sulfur and phosphorus may be used, as for example H_2SO_4 , H_3PO_4 and the various sulfonic acids.

In the present invention any suitable aldehyde may be employed as for example, acetaldehyde, propionaldehyde, butyraldehyde, benzaldehyde and acrolein. The preferred treating agent comprises formaldehyde which may be used as such, but is preferably utilized in a commercial operation as an aqueous solution. A particularly desirable aqueous solution comprises formalin (37% formaldehyde in water). However, it is to be understood that with respect to the present invention, if an aqueous carrier be employed the concentration of the added acid must be adjusted accordingly, since the acid concentrations specified are defined with respect to the total water present in the treating zone irrespective as to whether the water is introduced with the acid, or aldehyde or from other sources.

Other substances such as paraformaldehyde, trioxane, hexamethylene tetramine, methylal or equivalent substances which yield formaldehyde may be utilized.

Having described the invention it is claimed:

1. Improved process for removing constituents from hydrocarbons boiling in the motor fuel boiling range which tend to cause engine uncleanliness when burned in internal combustion engines which comprises contacting a liquid petroleum hydrocarbon boiling in the motor fuel boiling range with a dilute aqueous mineral acid of about 30-80% concentration and containing from about .5 to 5% of an aldehyde by weight based upon the hydrocarbon feed.

2. Process as defined by claim 1 wherein said

petroleum hydrocarbon comprises a cracked petroleum hydrocarbon.

3. Process as defined by claim 1 wherein said dilute acid comprises sulfuric acid and said aldehyde comprises formaldehyde.

4. Process as defined by claim 1 wherein said acid comprises sulfuric acid having a concentration in the range from about 55% to 65%.

5. Process as defined by claim 1 wherein said petroleum hydrocarbon boils in the range from about 100° F. to 400° F.

6. Improved process for the production of a high quality gasoline, which comprises contacting a liquid cracked petroleum fraction boiling in the motor fuel boiling range with a dilute mineral acid of about 30-80% concentration and containing from about .5 to 5.0% of formaldehyde by weight based upon the hydrocarbon feed, separating the acid layer, contacting the treated hydrocarbon fraction with a caustic solution and then redistilling the same.

7. Improved process for the production of high quality motor fuels from cracked distillates which comprises adding to said cracked distillates from about .5 to 5.0% of formaldehyde, mixing the formaldehyde and the distillate, thereafter adding to the distillate and the aldehyde a relatively dilute sulfuric acid of about 30-80% concentration, separating the acid sludge therefrom, treating the distillate with water and then with a dilute caustic, separating the treated distillate and rerunning the same to segregate a hydrocarbon fraction boiling in the motor fuel boiling range.

8. Process as defined by claim 7 wherein the acid separated from the distillate is recycled.

9. Process for removing constituents from hydrocarbons boiling in the motor fuel boiling range which tend to cause engine uncleanliness when burned in internal combustion engines which comprises contacting a liquid petroleum hydrocarbon boiling in the motor fuel boiling range with from about 0.5 to 10 volumes percent of a dilute aqueous mineral acid of about 30-80% concentration and from about .5 to 5% of an aldehyde by weight based upon the hydrocarbon feed.

10. Process as defined by claim 9 wherein said dilute acid comprises sulfuric acid and said aldehyde comprises formaldehyde.

50 ERVING ARUNDALE.
LOUIS A. MIKESKA.
